UNITED STATES PATENT OFFICE

2,538,308

PORTABLE GRAIN AND HAY ELEVATOR

Carl B. Grahl, Skidmore, Mo.

Application March 31, 1948, Serial No. 18,182

3 Claims. (Cl. 198—233)

1

This invention relates generally to elevators and more particularly to a portable elevator of a type adapted to be hitched to a motor vehicle, the conveyor per se being adjustably mounted on a carriage having ground contacting wheels.

A primary object of the invention is to provide a portable conveyor which has an elongated trussed frame with a hopper pivotally secured to what may be considered herein as the lower or forward end, the hopper being foldable upwardly and rearwardly onto the top of the frame when it is desired to hitch the conveyor to a motor vehicle, this hopper having an endless conveyor incorporated therewith, no disconnection of the conveyor or hopper being necessary in order to pivot the hopper into operative or inoperative positions.

Another object of this invention is to provide improved means whereby one end of an elongated conveyor may be raised and lowered, the carriage having ground contacting wheels and being connected to the elongated frame by a rigid member which is pivoted to the frame and winch and cable means being provided to shift the carriage pivotally with reference to the frame thereby raising and lowering one end thereof.

Still another object of this invention is to provide cradle means incorporated with the carriage and adapted to cooperate with rigid members connecting the axle of the carriage to the frame in order to support the mid-section of the frame when the winch and cable means is in inoperative position.

And a last object to be mentioned specifically is to provide a portable elevator which may be easily adapted for use in handling many different types of material, including bulky material such as baled hay, which is very safe and convenient to operate, and which will give generally efficient and durable service, while being relatively inexpensive and practicable to manufacture.

With these objects definitely in view, this invention resides in certain novel features of construction, combination and arrangement of elements and portions as will be hereinafter described in the specification, particularly pointed out in the appended claims, and illustrated in the accompanying drawings which form a material part of this application, and in which:

Figure 1 is a top plan view of the assembled elevator;

Figure 2 is a side elevational view of the assembled elevator, a corner portion of a bin being represented in dash line;

Figure 3 is another side elevational view of the elevator with the hopper folded upwardly and

2

rearwardly onto the top of the frame of the elevator and with the other end of the elevator lowered, as when the device is being transported while hitched to an automotive vehicle, which vehicle is fragmentarily represented in the figure;

Figure 4 is an enlarged longitudinal vertical sectional view through the hopper and adjacent structure at the front end of the elevator;

Figure 5 is a similar longitudinal vertical sectional view of the other or upper end portion of the elevator, the figure including a portion of the spout incorporated therewith;

Figure 6 is a transverse vertical sectional view, taken on the line 6—6 in Figure 2;

15 Figure 7 is a similar vertical transverse sectional view taken on the line 7—7 in Figure 4; and,

Figure 8 is an enlarged view of a drive shaft assembly having a slip clutch incorporated therewith, this structure being also represented in Figure 1.

Similar characters of reference indicate similar or identical elements and portions throughout the specification and throughout the several views 25 of the drawings.

Referring now to the drawings in detail, the environment wherewith this invention is adapted to be used, includes a motor vehicle of truck type, generally indicated at 10 in Figure 3, this vehicle 30 having hitch means 12 adapted to connect with the hitch means 14 on the forward end of the main portion of the elevator frame.

This main portion of the elevator frame will be hereinafter designated merely as the frame 16 and will be seen to comprise an elongated trussed frame in which the trusses 18, transversely disposed floor supporting members 20, longitudinally disposed floor members 22, lower corner angle bars 24, and transverse and longitudinally disposed guide members 26 and 28, and top rails 30 are all electric welded to provide a very rigid body or frame. Cross braces 32 disposed intermediate the height of the frame and preferably secured to the lateral longitudinal frame members 28, are used to support a false floor 34 upon which the upper flight of an endless conveyor 36 travels, according to conventional practice, the conveyor having a pair of laterally disposed chains and transversely disposed spaced scoops 38 which may 45 be of any desired configuration, and the said endless chains are driven by sprocket wheels 40, indicated in Figure 4, carried by a shaft 42, and there is provided at the upper end of the elevator a similar shaft 44 and a pair of sprocket wheels 46. 50 The shaft 42 is driven by a sprocket wheel 48

which is in turn driven by a sprocket chain 50 and another sprocket wheel 52 on a drive shaft 54, and the shaft 54 is driven by a belt 56 and a pulley 58 connected to an electric motor 60. The electric motor 60 is supported upon the platform 62 carried by straps 64 welded to the frame 16. In order that the endless conveyer shall be properly tautened, chain tightener assemblies 66 will be associated with the shaft 44 and the contiguous portions of the upper end of the frame.

In the drawings, the chain tightener assemblies 66 are represented as mounted on the lateral plates 68 of what will be termed the delivery head on the upper end of said frame. It will be clear from an inspection of the figures, that this delivery head includes a funnel portion 70 supported by the side plates 68, and the head plates 72 are made removable, so that bulky material such as baled hay and the like may be handled by the elevator. The funnel member 70 terminates in a collar 74 which has an annular groove to receive an inturned lip 76 of a supporting ring 78. This ring is represented as split and held in position on the collar 74 by means of a bolt or rivet 80, and the ring has a spout 82 pivoted thereon as at 84. This construction allows the spout 82 to be shifted into a very large number of positions relative to the delivery head on the upper end of the elevator.

A carriage, generally indicated by the numeral 86 is provided to make the elevator mobile, and this carriage includes a pair of ground-contacting wheels 88 on an axle 90, and the axle is rigidly secured to a rigid supporting member 92 which is, in turn, pivoted as at 94 on attachment plates 96 welded or otherwise properly secured to the sides of the frame intermediate the ends thereof. It will be understood that a plurality of these attachment plates 96 each with a pivot connection means 94 may be supplied so that the carriage may be selectively secured to the different plates 96 when it is desired to improve the balance of the elevator on the carriage by shifting of the carriage relative thereto, as when the delivery head plates and spout, and/or the hopper assembly 98, hereinafter described, are removed as when the elevator is being used for transporting bulky materials such as baled hay. In order to raise and to lower the delivery head end of the elevator, a windlass assembly including a reel 100, ratchet wheel 102 and pawl 104, reduction gears 106 and a crank handle 108, is mounted on one side of the elevator frame, the pawl being preferably equipped with an operating handle 110 and the cable 112 being preferably wound double on the reel 100. The two parts of the cable 112 are led through pulleys 114 on the axle 90 and through other pulleys 116 which may conveniently be mounted upon the platform 62, the ends of the cable or cable parts are secured to the reel 100 and the axle 90, and actuation of the crank handle 108 will cause the shortening or lengthening of the effective length of the cable 112 and the resultant pivotal action of the carriage raises and lowers the end of the elevator illustrated as to the right in the figures. The forward end of the frame is provided with end reinforcing angle members 118 and nose plates 120, the hitch 14 being mounted thereon, and it will be noted that the upper portions of the nose plates 120 are apertured to receive a shaft 122 which functions as a drive shaft for an endless conveyor 124, this drive shaft being driven by a sprocket 126 and a sprocket chain 128 entrained over another sprock-

et wheel 130 on the shaft 42, while the usual complement of sprocket wheels 132 are provided on intermediate portions of the shaft 122 to directly contact the drive chains of the endless conveyor 124. It is preferred that chain tightener sprockets 134 and 136 should be provided to preserve the proper tautness in the chains 128 and the chains 50 associated with the main endless conveyor 36. The shaft 122 also functions as a pivotal support for the hopper assembly 98, and it will be noted that this hopper assembly includes an upwardly inclined portion 140 and a normally horizontally disposed portion 142. The hopper is supplied with a center post structure 144 adapted to contact intermediate portions of the top rails 30 of the elevator frame when the hopper is pivoted upwardly and rearwardly as when the elevator is being transported from place to place and hitched to an automotive vehicle 10. It is thought unnecessary to describe in great detail the endless conveyor 24 provided in the hopper 98, but it may be noted that it is driven from the shaft 122 and that two other shafts 146 and 148 with suitable sprocket wheels or simple rollers will be incorporated with the hopper and will coat with laterally disposed guide rails 150 to preserve the endless conveyor in proper positional relationship within the hopper, all as will be clearly understood from an inspection of Figure 4. The endless conveyor 124 will be provided with scoops 152 of any suitable character, and a chain tightener assembly may be provided for each end of the shaft 148, as illustrated at 154 in Figure 2.

Finally, it should be noted that the drive shaft 54 will be provided with a slip clutch 156 with a biasing spring 158 and an adjusting nut 160, so that an obstruction in the main elevator or in the endless conveyor 124 will allow the stoppage of the major portion of the moving parts of this machine, while allowing the electric motor 60 to keep turning, thus preventing injury to both motor and machine. The carriage has a cradle comprised of laterally disposed rigid members 162 carried on the axle 90 and braced as at 164, along with a transversely disposed cross member 166, indicated in dotted lines in Figure 2 and adapted to support the frame 16 in cooperation with the rigid brace member 92. The upper ends of the members 162 form the sides of the said cradle and a brace 168 is connected to and between the rigid members 92 and 162.

The operation of this invention will be clearly understood from the foregoing description of the mechanical details thereof, taken in connection with the above recitation of the objects. In recapitulation, it may be added that the spout 82 and ring 78 will be conveniently stored, as indicated in Figure 3, on the top of the frame 16, when the machine is in transit. It may be noted that the members 144 may be connected by a cross member 170, preferably constructed of angle iron, and this cross member rests upon the top rails 30 of the frame 16 when the hopper is in position illustrated in Figure 3. The false floor 34 may be formed integral with vertical sides 172 and it is preferred that this floor and sides construction should be provided in relatively short sections to facilitate replacement of portions damaged in use, without replacement of the complete floor and side members. Elongated runners 174, ordinarily constructed of wood, are secured to the false floor 34 and positioned so that top flight chain portions of the endless elevator 36 ride thereon, this construction having

been found to greatly lessen the cost of maintenance of the machine. A rubber cushion 176, indicated clearly in Figure 4, is inserted on an inturned flange portion 178 on the lower end plate 180 of the main elevator structure, and this rubber cushion contacts the rearward lower side of the hopper when the same is in horizontal or operative position.

Obviously, many minor variations may be made in the exact construction and proportionment of the various elements of this invention without departure from the spirit and scope thereof. Accordingly, the scope of this invention should be determined only by a proper interpretation of the terminology used in the subjoined claims.

Having described the invention what is claimed as new is:

1. A portable elevator comprising an elongated frame, a carriage having ground-contacting wheels on an axle, a rigid member connected to said axle and pivoted on an intermediate portion of said frame, extensible means connecting a lower portion of the frame and said axle to raise and lower the other end of the frame, a power driven endless conveyor substantially co-extensive in length with and operatively mounted on said frame, said carriage having a cradle including opposed lateral arms and a cross member secured to and between said arms, said cradle being rigidly supported with respect to said axle and said rigid member and adapted to receive an intermediate portion of said frame and to cooperate with said rigid member in supporting the frame on the axle when said extensible means is fully extended.

2. A portable elevator comprising an elongated frame, a carriage having ground-contacting wheels on an axle, a rigid member connected to said axle and pivoted on an intermediate portion of said frame, said carriage having a cradle including opposed lateral arms and a cross member secured to and between said arms, said cradle being rigidly supported with respect to said axle and said rigid member and adapted to receive an intermediate portion of said frame and to co-

operate with said rigid member in supporting the frame on the axle when said extensible means is fully extended, extensible means connecting a lower portion of the frame and said axle to raise and lower the other end of the frame, and a power driven endless conveyor substantially co-extensive in length with and operatively mounted on said frame, said extensible means comprising a winch on said frame, a pulley on said axle, and a cable extending through said pulley and terminally secured to said winch and to said frame so that the frame may be raised and lowered by actuation of said winch.

3. A carriage for a portable elevator including a frame, said carriage comprising ground-contacting wheels on an axle, a rigid member connected to said axle and pivoted on intermediate portion of the frame of the elevator, extensible means connecting the lower portion of the frame and said axle to raise and lower the other end of the frame, a cradle including opposed lateral arms and a cross member secured to and between said arms, said cradle being rigidly supported with respect to said axle and said rigid member and adapted to receive an intermediate portion of said frame and to cooperate with said rigid member in supporting the frame on the axle when said extensible means is fully extended.

CARL B. GRAHL.
